UNITED STATES PATENT OFFICE.

EDWARD T. HURLEY, OF CINCINNATI, OHIO.

DESIGN FOR A BOWL OR SIMILAR ARTICLE.

Application filed March 12, 1928. Serial No. 25,800. Term of patent 7 years.

To all whom it may concern:

Be it known that I, EDWARD T. HURLEY, a citizen of the United States of America, and a resident of Cincinnati, in the county of Hamilton and State of Ohio, have invented a new, original, and ornamental Design for a Bowl or Similar Article, of which the following is a specification, reference being made to the accompanying drawing, forming a part thereof.

The dominant feature lies in the special grouping and in the various attitudes of the turtles.

Fig. 2 is a view taken on line 2—2 of Fig. 1.

I claim:

The ornamental design for a bowl or similar article as shown and described.

EDWARD T. HURLEY.
